UNITED STATES PATENT OFFICE

2,561,986

RECESSED LIGHT FIXTURE WITH
SEPARATE OUTLET BOX

Preston A. Jones, Berkeley, Calif., assignor of
one-half to Samuel L. Beber and Jerome H.
Feig, both of Los Angeles, Calif.

Application June 6, 1949, Serial No. 97,415

5 Claims. (Cl. 240—78)

1

This invention relates to light fixtures and is particularly directed to the so-called recessed type of fixture in which the same is provided with a light source cavity having an opening in substantial registry with a wall or ceiling surface. In general such an opening is arranged to be releasably covered by a glass or other translucent pane supported by portions of the frame.

An object of the present invention is to provide a recessed lighting fixture in which means are incorporated for greatly reducing the large amount of heat normally transferred between the light source within the fixture and the electrical wiring supplying current thereto.

Another object of the invention is to provide a fixture of the character described in which conventional wiring may be economically yet safely utilized in place of the excessively heavy heat insulated wires heretofore required in like installations.

A further object of my invention is to provide a light fixture of the type referred to in which ready access may be had to the electrical supply wires without the necessity of removing the fixture from its fixed recessed position.

A still further object of the invention is to provide a fixture of the above character in combination with a spaced ventilated electrical terminal or outlet box whereby heating of the latter due to conduction and radiation from the fixture light source is reduced to a minimum.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawing and description may be adopted within the scope of the invention as set forth in the claims.

Referring to the drawing:

Figure 1 is a plan view of the fixture and outlet or wiring compartment of the present invention.

Figure 2 is a cross-sectional view taken in the plane indicated by the line 2—2 of Figure 1.

Figure 3 is a cross-sectional view taken in the plane indicated by the line 3—3 of Figure 1.

In broad terms, the fixture of the present invention includes a housing generally indicated by the numeral 11 which is arranged to receive a lamp or other suitable light source, and a wiring compartment 12 disposed in spaced relationship to the housing but adapted for electrical connection therewith. The housing 11 is preferably

2

of rectangular form and includes a bottom 13 and side walls 14, 16, 17 and 18 respectively, the said bottom and walls defining the light-receiving cavity 19 or interior of the housing. In practice, the housing is installed in a recess provided in a wall or ceiling of a room with the open face of the housing substantially flush with the wall or ceiling surface. To secure the housing in such position, angle brackets or similar means may be secured to opposed sides 16 and 18 of the housing and similarly secured to the studs or joints of the building structure, but as this practice is conventional and forms no part of the present invention, it has not been illustrated in the drawing.

A suitable lamp, not shown, may be engaged in a socket 21 disposed within cavity 19 and mounted on a bracket 22 secured to bottom 13 and one or more of the side walls. As is well known, upon energization of the lamp element, a large amount of heat is radiated therefrom, and heretofore, due to the close proximity of the lamp and the electrical connections therefor, it has been necessary to heavily insulate both the lead wires and the connector wires. The present invention overcomes this objectionable requirement by substantially isolating the housing 11 from the wiring or terminal compartment 12 while at the same time permitting ready access therebetween. As here shown, the wiring compartment is generally cube-like in form and preferably includes fixed sides 23, 24, and 26, a removable bottom 27 and top 28, and a removable side 29 adjacent to and spaced from side 17 of the housing. The removable portions of the compartment may be secured to the fixed sides thereof by means of screws 31 engageable with suitably threaded apertures provided in lugs or ears 32 extending from such sides. Compartment 12 is secured to the housing in fixed spaced relation by means of brackets 33 which may be spot welded or otherwise secured to housing side 17 and sides 23 and 26 of the compartment.

Lead or supply wires 34 are brought into compartment 12 through a conduit 36 which may enter the compartment through suitable apertures provided in any of the walls thereof, and connector wires 37 connected to the socket 21 are arranged to pass into the compartment for interconnection with the lead wires 34 through a duct 38 in communication with the interior of the compartment and the housing cavity.

As an important feature of my invention, means are provided for permitting access to the wire compartment from the interior of the

housing. This may be effected by providing an opening 39 in housing side 17, the said opening being in substantial registry, but spaced from, the side 29 of the wiring compartment 12. Normally, a removable closure plate 41 is secured to the inner surface of side 17 by means of nuts 42 operatively connected to studs 43 mounted on the side, and when it is desired to install or inspect the wiring in the compartment, it is only necessary to remove the plate 41 and the side 29 of the compartment, the opening 39 being of a size sufficient to permit limited entry of the mechanic's hand or tools therethrough. The interiors of the wire compartment and the housing are normally isolated by either the plate 41 or side 29, and due to the arrangement of the parts, the air space between these interiors will act as a heat insulator, although it will be apparent that other insulating material could be used in this space.

I claim:

1. A lighting fixture adapted to be mounted in a wall or ceiling comprising a lamp housing, said housing having a removable side portion adapted to be mounted flush with the wall or ceiling and having an opening in another of its side portions, an outlet box, means for detachably securing the outlet box on the outside of said housing and spacing it therefrom, said outlet box having a removable side portion opposite and adjacent the opening in the said side portion of said housing whereby access may be had to the interior of said outlet box from the interior of said housing, conduit means extending from said outlet box to said housing and a removable cover for the opening in the said side portion of said housing.

2. A lighting fixture comprising a lamp housing adapted to be mounted flush with a wall or ceiling, said housing having an opening in one of its side portions, a removable cover for said opening, an outlet box, means for mounting said outlet box on the outside of said housing and spacing it therefrom, said outlet box having a removable side portion opposite the opening in the said side portion of said housing whereby access may be had to the interior of said outlet box from the interior of said housing and conduit means extending from said outlet box to said housing.

3. A lighting fixture comprising a lamp housing having side portions adapted to be mounted in a wall or ceiling, an opening in one of said side portions, an electrical outlet box, means for mounting said outlet box on the outside of said

housing opposite said opening and spacing it therefrom, said outlet box including an opening opposite and adjacent the opening in said housing side portion whereby access may be had to the interior of the outlet box from the interior of said housing, conduit means providing electrical connections extending from said outlet box to said housing, and means forming a removable closure for one of said openings accessible from inside said lamp housing.

4. A lighting fixture comprising a lamp housing having side portions adapted to be mounted in a wall or ceiling, an opening in one of said side portions, an electrical outlet box, means for mounting said outlet box on the outside of said housing opposite said opening and spacing it therefrom, said outlet box including an opening opposite and adjacent the opening in said housing side portion whereby access may be had to the interior of the outlet box from the interior of said housing, conduit means providing electrical connections extending from said outlet box to said housing, and means forming a removable closure for said side portion opening accessible from inside said lamp housing.

5. A lighting fixture comprising a lamp housing having side portions adapted to be mounted in a wall or ceiling, an opening in one of said side portions, an electrical outlet box having in a side thereof an opening of an area corresponding to the cross-sectional area of the interior of said box, means for mounting said outlet box on the outside of said housing opposite the opening in said side portion and spacing it therefrom, said housing opening being opposite and adjacent the opening on said outlet box and being of an area substantially at least as great as that of the outlet box opening whereby unrestricted access may be had to the interior of the outlet box from the interior of said housing, conduit means providing electrical connections extending from said outlet box to said housing and means forming a removable closure for one of said openings accessible from inside said lamp housing.
